(57) **CLAIM**

The ornamental design for a “brainwave alarm device,” as shown and described.

DESCRIPTION

FIG. 1 is a perspective view of brainwave alarm device showing our new design;

FIG. 2 is another perspective view of brainwave alarm device showing our new design

FIG. 3 is a front view thereof;

FIG. 4 is a rear view thereof;

FIG. 5 is a left side elevational view thereof;

FIG. 6 is a right side elevational view thereof;

FIG. 7 is a top view thereof; and,

FIG. 8 is a bottom view thereof.

The dashed lines in FIGS. 1-8 show the environment and do not form a part of the design sought to be patented.

1 Claim, 6 Drawing Sheets
